(57) **CLAIM**

The ornamental design for a bottle closure, as shown and described.

DESCRIPTION

FIG. 1 is a perspective view of a bottle closure of the present design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an inside perspective view thereof;

FIG. 9 is another inside perspective view thereof; and,

FIG. 10 is a view of the bottle closure applied to a bottle environment.

The broken lines showing a bottle are included for the purpose of illustrating environmental structure and form no part of the claimed design.
